BLASTING CAP

Don F. North, Castle Shannon, Pa., assignor to
 Hercules Powder Company, Wilmington, Del.,
 a corporation of Delaware

Application July 29, 1933, Serial No. 682,752

5 Claims. (Cl. 102—10)

This invention relates to blasting caps and more particularly to a blasting cap provided with means whereby actual firing through contact of the lead wires with a source of current will be positively avoided.

In order to avoid the accidental ignition of blasting caps adapted for electrical firing, it has been customary to provide means for short circuiting the lead wires until ignition is to take place. The preferred type of short circuiting arrangement involves the use of a bridging member for the uninsulated ends of the lead wires, which bridging member is adapted to be readily removed before firing takes place. A very satisfactory type of bridging member is shown in the patent to Barab 1,895,438, dated January 31, 1933. This comprises an eyelet of soft material in a peripheral groove of which the lead wires are clamped to provide the necessary short-circuit. The present invention is applicable to blasting caps associated with short circuiting conducting members of various forms having, however, the characteristic of that disclosed in the Barab patent in that they are readily removed by the application of moderate force. Some short-circuiting members of this type, for example, consist of conductors soldered across the wires or comprise metallic plates having their ends turned inwardly about the wires and clamped thereon the metal being soft and thin so that disengagement may be readily effected when desired, although accidental disengagement is substantially prevented.

One drawback in connection with such short circuiting members is that they are located at the ends of the relatively short lead wires directly connected to the caps. Their removal has accordingly necessitated the presence of a workman dangerously close to the charge to be fired with the possibility that if there happened to be a voltage applied to the firing circuit an immediate explosion might occur as soon as the short circuit is broken.

To avoid this difficulty means have been proposed for removing the short circuiting member by manipulation at a safe distance from the blasting cap. One suggestion heretofore made involves the use of a separate cord, or the like, which may be manipulated at a distance. It has also been suggested to connect the short circuiting member with a cord secured to the firing circuit at a distance from the short circuiting member which is greater, when measured along the firing circuit, than the cord itself. A sharp pull on the firing circuit will in such case dislodge the short circuiting member to prepare the setup for

firing. The use of such auxiliary device, however, is objectionable in that if the auxiliary cord is free the cord may become twisted in the lead wires with the possibility that during unreeling of the wires the short circuiting element will be disconnected. The danger of this is even greater when the cord is attached in any fashion inasmuch as handling of the wires is likely to result in a premature interruption of the short circuit. 5

It is the object of the present invention to provide an arrangement whereby without the provision of any auxiliary means but by a mere arrangement of the lead wires and firing circuit wires provision is made for interrupting the short circuit located a short distance from the blasting cap. 10 15

Both the broad objects of the invention and the specific ones relating to desirable details will become apparent from the following description read in conjunction with the accompanying drawing in which:

Fig. 1 illustrates diagrammatically a firing circuit prior to the interruption of the short circuit;

Fig. 2 is a similar view of the same showing the opening of the short circuit and preparation of the circuit for firing; and

Fig. 3 is an enlarged plan view showing a blasting cap, its associated lead wires and a short circuiting member provided in accordance with the invention. 25 30

Referring first to Fig. 3 there is illustrated at 2 a blasting cap of the conventional type provided with an igniter in which is located a filament whose ends are connected to the insulated lead wires 4 and 6 provided with uninsulated end portions 8 and 10. The lead wire 6 in the present instance is substantially longer than the lead wire 4 being provided with a portion 12 doubled back on itself as indicated in the figure. The difference in length is such that the insulated length of lead wire 6 is greater than the total length of the lead wire 4 including its uninsulated portion. There is provided at 14 a short circuiting member of the type illustrated in the Barab patent although it will be understood that this short circuiting member may be of any form adapted to be released from the wires by the imposition of the type of effort indicated below. Preferably the uninsulated portion of lead wire 6 indicated at 10 extends beyond the short circuiting member 14 further than the uninsulated portion 8 of the lead wire 4. This merely serves as an indication that the end 10 corresponds to that lead wire which is the longer. 35 40 45 50 55

There is indicated diagrammatically at 16 a blasting machine of the usual type designed to furnish the current for firing the cap. Firing wires 18 and 20 are connected to this machine and are electrically secured to the uninsulated ends of the lead wires 4 and 6 as indicated at 22 and 26. The firing wire 18 which is connected to the shorter lead wire 4 is made extra long as indicated at 24, its excess length over the firing wire 20 being preferably of the order of the excess length of the lead wire 6 over the lead wire 4. Originally the firing circuit will be as indicated in Fig. 1. All of the lengths of this figure are, of course, considerably shortened, the lead wires being of substantial length but not of a length corresponding to a safe distance from the charge, while the firing wires are of very considerable length so that the blasting machine is at a safe distance. By pulling upon the firing wires adjacent the blasting machine, or at any intermediate safe distance, strains will be imparted to the short circuiting member serving to disengage it from at least one of the lead wires. Pulling the wires further will serve to bring the uninsulated portions of one opposite the insulated portions of the other as indicated in Fig. 2 so that even though the wires themselves might accidentally twist together or overlap each other there will be definite assurance that there will not exist in the circuit any short. The difference in length of the two lead wires is greater than the uninsulated portion of the shorter wire and, furthermore, the insulated portion of the longer wire is of greater length than the total extent of the shorter wire. This insures that the uninsulated portions of the two lines will not come into opposition after extension takes place.

While any desirable means may be provided to identify the longer of the lead wires and also the longer of the wires of the firing circuit, it is very convenient to make the provision indicated above, namely, that the uninsulated end beyond the short circuiting member of one wire be greater than the corresponding end of the other.

It will be obvious that numerous variations may be made in the embodiment of the invention without departing from the spirit thereof as defined in the following claims.

What I claim and desire to protect by Letters Patent is:

1. In combination, a blasting cap adapted for electrical firing, lead wires from the cap having uninsulated end portions, and a removable conducting member connecting the uninsulated end portions of the lead wires, one of said lead wires being of substantially greater length than the

other between the cap and the conducting member, the difference in length being greater than the uninsulated portion of the shorter wire.

2. In combination, a blasting cap adapted for electrical firing, lead wires from the cap having uninsulated end portions, and a removable conducting member connecting the uninsulated end portions of the lead wires, one of said lead wires being of substantially greater length than the other between the cap and the conducting member, the insulated portion of the longer wire being of greater length than the total extent of the shorter wire.

3. In combination, a blasting cap adapted for electrical firing, lead wires from the cap having uninsulated end portions, and a removable conducting member connecting the uninsulated end portions of the lead wires, one of said lead wires being of substantially greater length than the other between the cap and the conducting member, the difference in length being greater than the uninsulated portion of the shorter wire, and the insulated portion of the longer wire being of greater length than the total extent of the shorter wire.

4. In combination, a blasting cap adapted for electrical firing, lead wires from the cap having uninsulated end portions, a removable conducting member connecting the uninsulated end portions of the lead wires, one of said lead wires being of substantially greater length than the other between the cap and conducting member, whereby slack is provided in the wire of greater length between the cap and the conducting member, a current generator, and firing wires extending from the generator and having uninsulated end portions connected to the uninsulated end portions of the lead wires, the firing wire connected to the shorter lead wire being longer than the other whereby slack is provided in the longer wire between the generator and the conducting member.

5. In combination, a blasting cap adapted for electrical firing, lead wires from the cap having uninsulated end portions, and a removable conducting member connecting the uninsulated end portions of the lead wires, one of said lead wires being of substantially greater length than the other between the cap and the conducting member, and the end portion of one lead wire beyond the conducting member being longer than the corresponding end portion of the other, the insulated portion of the longer lead wire being of greater length than the total length of the shorter lead wire.

DON F. NORTH.
